GAME TALLY HOLDER

Paul D. Spillane, Belmont, Mass.

Application February 23, 1934, Serial No. 712,664

1 Claim. (Cl. 45—75)

The present invention relates to a game tally holder for use in card tables where game scores are necessary and the object of the invention is to provide a device of this nature whereby any and all players at a glance can see the score all the time. It does away with the necessity of looking for score pad when about to start play as it is always attached to the table. It does away with the removal of the score pad from the table to make room for playing. It does away with the necessity of the players asking the score during the game as it is always visible from all parts of the table. It is imperative in contract bridge that all players know the score at all times. This device keeps the score visible to them at all times. It is attached flush with the top of the table and in no way interferes with the playing of the cards.

Another very important object of the invention is to provide a device of this nature which is simple in its construction, easy to manipulate, inexpensive to manufacture, thoroughly efficient and reliable in use and otherwise well adapted to the purpose for which it is designed.

With the above and numerous other objects in view as will appear as the description proceeds, the invention consists in certain novel features of construction, and in the combination and arrangement of parts as will hereinafter be more fully described and claimed.

In the drawings:

Figure 1 is a top plan view of a card table showing the tally incorporated in one corner portion of the table.

Figure 2 is a sectional view taken substantially on the line 2—2 of Figure 1.

Figure 3 is a sectional view taken substantially on the line 3—3 of Figure 1.

Figure 4 is a perspective view of the box like frame.

Figure 5 is an end elevation thereof.

Figure 6 is a perspective view of the deflecting block.

Referring to the drawings in detail it will be seen that the card table is provided with a rectangular opening 5 in which this device is mounted so that the upper edge of the device is flush with the top of the table. The device consists of a rectangular box like frame including a pair of side walls 6 and 6, and end wall 7 and another end wall 8. On the lower edges of the side walls 6 there are provided outwardly directed flanges 9. On the upper edges of the side walls 6, 6 and the end wall 7 are inwardly directed flanges 10, 10 and 11. The flanges 11 terminate a distance

from the end wall 8. A strip 12 extends between the ends of the flanges 10 adjacent the end wall 8. A block 14 is mounted in the frame abutting the end wall 8 and the upper side thereof is beveled to incline upwardly away from the strip 12 and adjacent the wall 8 the beveled face 15 is more pronouncedly beveled as indicated at 16. Numeral 17 denotes a follower plate on which are mounted a plurality of tally sheets 18. A bowed spring 19 has its central portion fixed to the central portion of the follower plate 12. A bottom 20 has flanges 21 on its longitudinal edges slidably cooperable with flanges 9. When the bottom 20 is removed the follower 17 may be removed and tally sheets placed thereon. Then the tally sheets and follower plate are placed in the frame and then the bottom is slid into place. When the tally sheet has been used it may be slid out between the strip 12 over the bevel face of the block 14 as clearly illustrated in Figure 2.

It is thought that the construction, operation, utility and advantages of this invention will now be quite apparent to those skilled in this art without a more detailed description thereof.

The present embodiment of the invention has been described in considerable detail merely for the purposes of exemplification since in actual practice it attains the features of advantage enumerated as desirable in the statement of the invention and the above description.

It will be apparent that changes in the details of construction, and in the combination and arrangement of parts may be resorted to without departing from the spirit or scope of the invention as hereinafter claimed or sacrificing any of its advantages.

Having thus described my invention, what I claim as new is:

In combination with a table having an opening in its top passing vertically through said top, a frame fitting in the opening with its lower portion projecting below the lower face of the table, an inwardly extending flange on the upper edges of one end member and the two side members of the frame, said flange having those parts on the side members terminating an appreciable distance from the other end member of the frame, a cross piece extending across the frame and connected with the terminals of those portions of the flange which are carried by the side members of the frame, the flange being flush with the top of the table top, a bottom member slidably connected with the lower part of the frame for covering the bottom thereof, a block fitting in that part of the frame between the cross piece and the adjacent

end of the frame with the lower edge of the block resting on the bottom piece, the upper face of the block having an upstanding projection thereon adjacent the outer edge of the block, the inner face of said projection sloping upwardly and outwardly, the inner face of the block being slightly spaced from the cross piece to permit a sheet to be passed between the cross piece and the block,

the projection causing the sheet to pass upwardly above the table top, a follower in the frame for supporting sheets thereon, and a spring connected to the under face of the follower and engaging the bottom piece for pressing the sheets on the 80 follower against the flange and the cross piece.

PAUL D. SPILLANE.
